(57) **CLAIM**

The ornamental design for the “novelty lenses,” as shown and described.

DESCRIPTION

FIG. 1 is a front view of the novelty lenses;

FIG. 2 is a rear view thereof;

FIG. 3 is a top view thereof;

FIG. 4 is a bottom view thereof; and,

FIG. 5 is a right side view thereof, with the left side view being a mirror image thereof.

The broken lines are for purposes of illustration and form no part of the invention.

1 Claim, 5 Drawing Sheets
